United States Patent Office

Des. 184,477
Patented Feb. 24, 1959

184,477

CHRISTMAS ORNAMENT OR SIMILAR ARTICLE

Alfred A. Flaster, New York, N. Y.

Application March 31, 1958, Serial No. 50,237

Term of patent 3½ years

(Cl. D29—1)

Fig. 1 is a perspective view of a Christmas ornament or similar article showing my new design;

Fig. 2 is a front elevational view; and

Fig. 3 is a rear elevational view thereof.

The stippling indicates spangles.

I claim:

The ornamental design for a Christmas ornament or similar article, substantially as shown and described.
